O. C. HENCKEL.
WINDOW SASH LOCK.
APPLICATION FILED SEPT. 2, 1915.

1,182,481.

Patented May 9, 1916.

UNITED STATES PATENT OFFICE.

OLUF C. HENCKEL, OF BROOKLYN, NEW YORK.

WINDOW-SASH LOCK.

1,182,481.

Specification of Letters Patent.

Patented May 9, 1916.

Application filed September 2, 1915. Serial No. 48,711.

To all whom it may concern:

Be it known that I, OLUF C. HENCKEL, a citizen of the United States, residing at Brooklyn, in the county of Kings, State of New York, have invented certain new and useful Improvements in Window-Sash Locks; and I do hereby declare the following to be a full, clear, and exact description of the invention, such as will enable others skilled in the art to which it appertains to make and use the same.

The present invention is directed to improvements in window sash locks, and has for its object to provide a device of this character so constructed that the same can be easily and quickly applied to any form of sash.

A further object of the invention is to provide a sash lock constructed in such a manner that the upper and lower sashes can be positively locked in their closed position or in a partially open position.

A still further object of the invention is to provide a sash lock which is extremely simple in construction, durable, efficient in operation and one which can be manufactured at a very small cost.

With these and other objects in view, this invention resides in the novel features of construction, formation, combination and arrangement of parts to be hereinafter more fully described, claimed and illustrated in the accompanying drawing, in which:—

Figure 1 is a front elevation of the device showing it in place. Fig. 2 is a side elevation of the same. Fig. 3 is a top plan view of the device. Fig. 4 is a vertical central sectional view through the device.

Referring to the drawing 1 indicates the lower sash, and 2 the upper sash, the side rail of which is provided with a plurality of spaced vertically alined sockets 3, the purpose of which will appear later.

The lock consists of a base plate 4, the ends of which terminate in upstanding flanges 5, said flanges being provided with alined screw threaded openings 6, and in which is engaged the threaded rod 7, said rod having its inner end provided with a finger-piece 8, whereby said rod may be rotated, when desired. The inner end of the rod is provided with a disk 9 adapted to

impinge against the adjacent side rail of the upper sash. The base 4 is provided on its upper surface with a longitudinal groove 55 10, in which is engaged the lower end of the head 11. The head 11 is provided with upper and lower bores 12 and 13, respectively, the upper bore being engaged by the rod 7, while the lower bore is engaged by 60 the unthreaded portion 14 of the rod 15, said rod having a threaded portion 16, which is engaged in the threaded opening 17 formed in the outer flange 5. The rod 15 is provided with a shoulder 18, which is 65 adapted to engage the rear edge of the head 11 so that when the rod is rotated in one direction said head will be moved inwardly. The inner end of the rod 15 has carried thereby a pin 19, which is adapted to engage 70 the forward edge of the head 11 so that when the rod is rotated in a reverse direction, said head will be moved outwardly. To facilitate the rotation of the rod 15, the same is provided at its outer end with a finger-piece 20. The head is provided with a finger 21, which is adapted to engage a selected socket 3 in the side rail of the upper sash, thus locking the sashes against relative movement. The inner flange 5 terminates in 80 a depending plate 22, which is adapted to rest flush against the inner surface of the side rail of the lower sash, and at which time, the base 4 rests upon the upper end of said rail. Suitable securing devices are 85 passed through the base 4 and the plate 22 thereby firmly holding the lock in place.

In operation, the sashes are arranged in either closed or partially closed positions, after which the rod 15 is rotated so as to 90 move the head 11 outwardly, whereupon the finger 21 will engage a selected socket, thereby firmly locking the sashes together. The rod 7 is then rotated until the disk 9 thereof is impinged firmly against the adjacent side rail of the upper sash, and in conjunction with the finger 21, serves to firmly 95 lock the sashes.

What is claimed is:—

A sash lock comprising a base adapted to 100 be secured to the lower sash, said base having upstanding flanges at its ends, a head slidably associated with the base and having upper and lower bores formed therein,

a threaded rod supported by the flanges and engaged in the upper bore, said rod having a sash engaging disk carried by its outer end, a second rod threaded in one of the flanges and having an unthreaded portion for rotatably engaging the lowermost bore of the head, a finger carried by the head for engaging the upper sash when the sec-

ond named rod is rotated, and means for rotating said rod.

In testimony whereof, I affix my signature, in the presence of two witnesses.

OLUF C. HENCKEL.
